UNITED STATES PATENT OFFICE.

WALTER B. THOMAS, OF CHICAGO, ILLINOIS, ASSIGNOR TO THE McCONWAY & TORLEY COMPANY, OF PITTSBURG, PENNSYLVANIA.

CAR-COUPING.

SPECIFICATION forming part of Letters Patent No. 630,132, dated August 1, 1899.

Application filed March 12, 1898. Serial No. 673,562. (No model.)

To all whom it may concern:

Be it known that I, WALTER B. THOMAS, a citizen of the United States, residing at Chicago, in the county of Cook and State of Illinois, have invented certain new and useful Improvements in Car-Couplers, of which the following is a specification.

The invention relates to that species of couplers known as the "Master Car-Builders" type, and in essential features is practically automatic in locking, unlocking, and opening the knuckle, dispensing with springs, keys, and bolts and with the usual beveled bracket to support the lifting-rod in unlocking. By "automatic" it is intended to imply that the locking is entirely automatic, while the raising of the lifting-rod unlocks and automatically throws open the knuckle in one movement. In this construction only five movable pieces are used—to wit, the draw-head, the knuckle, the locking-lever, the pivot-pin, and the lifting-rod—and strain comes upon the first four of these alone and practically upon the first three, which are so arranged that they will hold the parts together even if the pivot-pin be broken.

The invention consists, in general terms, in combining with the knuckle and its rearwardly-projecting locking-arm a locking-lever so arranged and controlled that it falls over and locks the knuckle when the latter is closed, but tips and exerts leverage on the knuckle to open it when raised by the lifting-rod, in combining with the knuckle and its rearwardly-projecting locking-arm a locking-lever and tripping devices for said lever, whereby when the lever is raised it may be shifted upon supports above said locking-arm and held out of locking engagement therewith, in combining with the knuckle and its rearwardly-projecting locking-arm a locking-lever having a depending push-arm, a compound curved guideway, and a fixed fulcrum-stop for said locking-lever, whereby the push-arm is caused to act against the tail of the locking-arm in the direction of its path of opening movement, in forming the knuckle-locking arm with a groove inclined in a direction opposed to the direction of draft and the locking-lever with a coacting rib, whereby strain upon the knuckle tends to tighten

the lock and make it more secure, and in the various other combinations and details of construction hereinafter pointed out and claimed.

In the drawings, Figure 1 is a front elevation, partly broken away to disclose the effective parts more completely, of a coupler embodying my invention. Fig. 2 is a top plan view, partly diagrammatic, of said coupler; Fig. 3, a side elevation, also partly diagrammatic; Fig. 4, a horizontal section therethrough on the line 4-4 in Fig. 3; Fig. 5, edge and side elevations of a guard-disk for the lifting-rod with a fragmentary enlarged detail thereof; Fig. 6, a fragmentary detail of the knuckle-locking arm and its inclined groove with a section through the locking-lever to show the inclined rib; Fig. 7, fragmentary details, in top plan and cross-section, of the knuckle-locking arm to explain the notch therein. Fig. 8 is a side elevation of the coupler, including the buffer-beam, to show the arrangement and connection of the lifting-lever. Fig. 9 is a horizontal section through the coupler upon the correspondingly-numbered line in Fig. 3; and Fig. 10 is an inside elevation of the front plate or wall of the chambered draw-head, showing the guide. Figs. 11 and 12 are detail views of the guideway.

A represents the draw-bar, having its projecting head A' formed to afford a chamber or casing and bearings for the knuckle and other parts of the coupler.

B is the knuckle, swinging on pivot-pin b and having a locking-arm B', closing into the casing. This locking-arm is notched or grooved at b' for the reception of a tongue from the locking-lever, as explained below. The rear end or tail of the locking-arm is beveled, as at b'', and the rear wall of the chambered draw-head has a beveled buffing-lug B'', matching the bevel upon the locking-arm to resist endwise thrust upon the knuckle. Obviously the fit must not be so snug as to prevent the knuckle from swinging open upon its pivot, and obviously, also, the bevels need not be plane faces, but may be described on arcs concentric with the axis of movement of the knuckle.

C is the locking-lever, located in a guide-

way C' to the rear of the knuckle, having a vertical push-arm c, arranged at the back of the locking-arm of said knuckle and a horizontal extension c' saddling the locking-arm and 5 terminating in a depending engaging block c², which fills the space between the wall c³ of the guideway and the front of the locking-arm when the knuckle is closed and shuts down past said arm to lock the knuckle against 10 opening. A rib c⁴ upon the inner face of the block takes into the groove b' in the locking-arm and serves to prevent the knuckle being withdrawn in case the pivot-pin breaks. The groove is advisably made somewhat inclined 15 from the vertical, as is the rib also, so as to prevent the locking-lever from working up and out of engagement by friction. The inclination is away from the direction of strain on the knuckle, so that such strain 20 will only tend to make the lock more secure.

A rod D serves to raise the locking-lever in its guideway to disengage the knuckle, and since the lever is to be so controlled that its 25 push-arm will force the knuckle open by being swung against the back of the locking-arm of said knuckle this lifting-rod is to be attached at d above the depending engaging block of said lever and must have sufficient play in its guide-opening to permit the somewhat 30 involved swinging movement of the lever, as presently to be described. Therefore to close this guide-opening and keep out dirt the lifting-rod is passed through a sufficiently close-fitting oblate disk D', which for 35 convenience in applying may be made in halves, tongued and grooved at d', and united at the periphery by dovetailed clips d², attached to one of the sections and taking into 40 corresponding dovetailed recesses d³ in the other, as shown in the edge elevation and in the enlarged detail.

The rod D, which may be called the "lifting-rod," is raised by the lifting-lever D², which is practically a bell-crank, shown as mounted 45 in horizontal bearings upon the front of the buffer-beam B² and having the horizontal arm d⁴ flexibly connected with the head of the lifting-rod, while the pendent arm or handle d⁵ normally hangs parallel with the end of 50 the car and rests against the front face of the buffer-beam or whatever part of the car it is mounted upon. Except when actuated to disengage the knuckle this lever-arm will always be in a pendent position whether the knuckle 55 is locked or unlocked.

The engaging block of the locking-lever travels in a guideway of peculiar outline. First, it curves up and over toward the push-arm of the lever, as at E in Fig. 1, so as to 60 swing the lever end of the push-arm against the locking-arm of the knuckle. Second, it curves up and inward, as at E' in Fig. 3, to give a resultant movement to the push-arm, causing it to follow the arc of movement of 65 said locking-arm as it kicks it open. To bring sufficient leverage upon the push-arm in this action, a lug F is extended rearward

from the horizontal member of the locking-lever adjacent to this push-arm and countersunk upon its upper side to engage with a conical fulcrum-stop F' after the lever has been lifted bodily some little distance, thus positively stopping the push-arm from further ascent and causing it to forcibly describe the resultant movement above referred to. This pushing capacity of the locking-lever will be utilized whenever the knuckle is to be thrown open for the purpose of coupling with cars backing down upon its own car or toward which the latter is being shot 80 or backed, the draft of the train opening the knuckle when a car is simply being dropped or kicked in switching or yard work; but it often happens that it is necessary or desirable to unlock the knuckle when there is no strain upon it to pull it open, as when a train is at a standstill, and leave it unlocked until the cars in front are started. For this purpose it is necessary that the locking-lever shall not come in contact with the vertical 90 fulcrum, but shall be lifted only so far that it can be shifted upon supports above the locking-arm of the knuckle, and that means for such shifting shall be provided. Accordingly the rear upper surface of the locking-arm adjacent to the push-arm is provided with a socket G, which is carried down and out through the back of the locking-arm, with a flaring opening g, so that dirt and debris may be discharged, and the adjacent side of 100 the push-arm is provided with a downward projection G', terminating in an inclined engaging shoulder g' at such point that when it rests in the socket the engaging block at the other end of the lever will rest upon a 105 ledge g² out of engagement with the locking-arm. The knuckle will then be unlocked, but not open, though readily opened whenever strain is brought upon it, while the engagement of the locking-arm with the socket 110 will be sufficient to prevent ordinary chance displacement and relocking. To cause the endwise movement of the locking-lever necessary to bring it into this position, a trip-stop H is located upon a vertical guide-rib 115 H' in position to engage the rearwardly-extending lug on the lever and push the lever over as it is lifted just sufficiently to cause it when released to drop into the socket and upon the ledge. This trip-stop H alone is 120 not sufficient for effective work, since it is liable to twist the lever by one-sided action. Therefore a second trip-stop H² is located upon another guide-rib H² on the inner side 125 of the front plate of the chambered draw-head in position to come into contact with a shoulder h upon the front of the locking-lever at the same moment that the first trip-stop strikes against the rearwardly-projecting lug, thus insuring uniformity of action. 130

When the knuckle is thrown open by the locking-lever and the latter released, it falls until the foot of the push-arm rests upon the base of the chambered draw-bar, while the

engaging block rests upon the above-mentioned ledge g^2 , the fulcrum-stop having the same agency as the trip-stops in shifting the position of the locking-lever. When the 5 knuckle is closed, its locking-arm strikes the shouldered projection upon the push-arm and pushes aside said arm and causes it to register with and drop through an opening K in the floor of the chambered draw-bar, releasing the engaging block from the ledge and permitting the locking-lever to drop and secure the knuckle. In case the lifting-rod breaks, or in any emergency, the coupling can be opened by lifting the protruding end 15 of the push-arm.

The locking-lever can never drop behind the knuckle-locking arm, even should it fail to be shifted far enough to engage with the ledge g^2 or should it be shaken off of such 20 ledge by the jarring of the car, for the reason that the tail of the locking-arm never passes entirely from beneath the locking-lever. Consequently should said lever fall from the ledge the engaging block will rest upon the 25 locking-arm in rear of the inclined groove therein and in position to fall into and engage with said groove whenever the knuckle is closed. This limitation of movement of the locking-arm is due to a stop k upon the 30 knuckle, which comes against the side of the draw-head at k' , while the tail of the locking-arm is still beneath the engaging block or that end of the locking-lever carrying the 35 engaging block and prevents its further withdrawal.

Between the knuckle and the locking-arm extends a rib L, midway between the lugs of said knuckle, which rib is intended to fit between the lugs of an opposing coupler to prevent uncoupling by up-and-down movement and to help carry the weight of the car in case the truck breaks down or jumps the track. In case the rear draft attachments give way under strain and the knuckle fails to unlock, 45 and the coupler is therefore pulled out entirely, it will be supported and prevented from falling upon the track by this rib between the lugs and the locking-arm resting between the lugs of the knuckle on the opposing 50 coupler and the corresponding rib upon the latter knuckle resting between the lugs of the knuckle on the coupler pulled out; but ordinarily whenever the draft attachments give way the strain of the lifting-lever on the 55 lifting-rod and through that upon the locking-lever will release the knuckle and it will open, uncoupling from the adjacent car before the coupler is pulled out or so far torn from its fastenings as to be in danger of falling upon the track.

The push-arm may be operated, but not as effectively, by employing the curved guide (shown in Fig. 1) and omitting the secondary curve, (shown in Fig. 3,) the other parts remaining the same.

I claim—

1. The combination with the knuckle and

its locking-arm having rearwardly-inclined groove, of the engaging block having rearwardly-inclined rib, the inclination of said 70 groove and rib being opposed to the direction of draft.

2. The combination with the knuckle and its locking-arm having a rearwardly-inclined groove, of the locking-lever having an engaging 75 block with a rearwardly-inclined rib arranged to drop between said locking-arm and the proximate wall of the chambered draw-head when the knuckle is closed, to lock it against opening.

3. The combination with the knuckle and its locking-arm having a rearwardly-inclined groove, of the locking-lever carrying an engaging block at one end to bar the movement 85 of said locking-arm, said block having a rearwardly-inclined rib, and having a depending push-arm at the other end, the ledge in the chambered draw-head, for the support of the block, a trip-stop to shift the locking-lever endwise, and means for lifting said locking- 90 lever.

4. The combination with the knuckle and its locking-arm having a socket in its rear upper face, of the locking-lever carrying an engaging block to bar the movement of said 95 locking-arm and having a depending arm with a shoulder to engage said socket, the ledge for the support of said block, a trip-stop to shift the locking-lever, and the lifting-rod.

5. The combination with the knuckle and 100 its locking-arm having a groove in its front face and a socket at its rear, of the locking-lever carrying an engaging block having a rib to enter said groove, and a depending arm with a shoulder to engage said socket, 105 the ledge for the support of the engaging block, a trip-stop to shift the locking-lever and the lifting-rod.

6. The combination with the knuckle and 110 its locking-arm, of the locking-lever carrying an engaging block at one end to bar the opening 115 of the knuckle, and a downwardly-projecting push-arm at the other end, and said locking-lever having a projection at its rear and a shoulder at its front, the ledge in the chambered draw-head, and the two ribs and trip-stops arranged to coact with said projection and shoulder to shift the locking-lever upon the ledge.

7. The combination with the knuckle and 120 its locking-arm having a socket in its rear upper face, of the locking-lever carrying an engaging block to bar the opening of the knuckle and having a depending arm with a shoulder to engage said socket, a rearward 125 projection and a trip-shoulder at its front, the ledge in the chambered draw-head, and the two ribs and trip-stops arranged to coact with the rearward projection and trip-shoulder, to shift the locking-lever upon the ledge and into 130 engagement with the socket.

8. The combination with the knuckle and its locking-arm, of the locking-lever having an engaging block at one end and a push-arm

at the other end, means for lifting said lever, and a compound guideway for said lever as it is lifted, whereby the push-arm is thrust against the locking-arm to open the knuckle.

5 9. The combination with the knuckle and its locking-arm, of the locking-lever having an engaging block at one end and a depending push-arm at the other end, means for lifting said lever, means for guiding the block 10 end of the lever as it is lifted, in a compound curve and a fulcrum-stop for the push end of the lever, whereby the push-arm is caused to move in a path corresponding with the path traveled by the locking-arm as the knuckle 15 is opened.

10. The combination with the knuckle and its locking-arm, of the locking-lever having an engaging block at one end and a depending push-arm at the other end, means for lifting 20 the lever, means for guiding the block end of the lever as it is lifted to guide the push-arm against the locking-arm, to open the knuckle, a ledge for the support of the block end, and a fulcrum-stop for the push 25 end, arranged to swing the push-arm against

the locking-arm, and to shift the lever over to position for engagement with the ledge.

11. The combination with the knuckle and its locking-arm of the locking-lever having an engaging block at one end and a push-arm 30 at the other end, the doubly-curved guideway for the engaging block, the fulcrum-stop, and the lifting-rod.

12. The combination with the knuckle and its locking-arm, of the locking-lever having 35 an engaging block at one end, a push-arm on the other, and a rearwardly-extending countersunk lug adjacent to said push-arm, the doubly-curved guide for said block, the lifting-rod, and the conical fulcrum-stop. 40

13. The oblate disk or washer having a central opening, and made in two pieces united by tongue and groove and peripheral dovetailed clips and recesses.

In testimony whereof I affix my signature 45 in presence of two witnesses.

WALTER B. THOMAS.
